Primary Examiner — Cathron C Brooks*Assistant Examiner* — Keith J Wilson(74) *Attorney, Agent, or Firm* — Birch, Stewart, Kolasch & Birch, LLP(57) **CLAIM**

The ornamental design for a water flow regulator, as shown and described.

DESCRIPTION

FIG. 1 is a first perspective view of a water flow regulator showing my new design;

FIG. 2 is a second perspective view of the water flow regulator;

FIG. 3 is a third perspective view of the water flow regulator;

FIG. 4 is a front view of FIG. 1;

FIG. 5 is a rear view of FIG. 1;

FIG. 6 is a left side view of FIG. 1;

FIG. 7 is a right side view of FIG. 1;

FIG. 8 is a top view of FIG. 1; and,

FIG. 9 is a bottom view of FIG. 1.
